UNITED STATES PATENT OFFICE.

JOSEPH WHITE, OF PISCATAWAY TOWNSHIP, AND WILLIAM ECKHARD, OF PLAINFIELD, NEW JERSEY, ASSIGNORS TO HALL PRINTING PRESS COMPANY, OF DUNELLEN, NEW JERSEY, A CORPORATION OF NEW JERSEY.

SHEET-GAGE.

1,341,694.

Specification of Letters Patent.

Patented June 1, 1920.

Application filed September 24, 1919. Serial No. 325,946.

To all whom it may concern:

Be it known that we, JOSEPH WHITE and WILLIAM ECKHARD, citizens of the United States, residing at Piscataway township, in the State of New Jersey, and Plainfield, county of Union, State of New Jersey, respectively, have jointly invented certain new and useful Improvements in Sheet-Gages, of which the following is a specification.

10 This invention relates to sheet gages and particularly to improvements in the form of gage illustrated in the prior patent of Joseph White, No. 1,178,563, granted April 11, 1916.

15 One of the objects of our invention is to provide a gage which will be moved out of the way of the sheet, positioned thereagainst, very rapidly and certainly and at the last possible moment. Another object of our 20 invention is to provide a gage of the above described character which can also be adjusted so that the distance which it extends across the sheet path can be adjusted.

With these and other objects in view, our 25 invention consists of certain novel features of construction, combination and arrangement of parts as will be more fully described and pointed out in the appended claims.

30 In the drawings, Figure 1 is a sectional elevation of a portion of a feeding apparatus embodying our present invention, and Fig. 2 is a plan view, with parts broken away, of Fig. 1.

The corresponding parts are referred to 35 both in the specification and in the drawings by similar reference characters.

As will be seen by a comparison of Fig. 4 of said prior Patent No. 1,178,563, many of the parts illustrated in this application are 40 identical with the parts shown in said patent, and for a more detailed description of said parts reference is made to said patent.

45 10 represents a part of a sheet carrier having a member 11 provided with gripper abutments 12 and a gripper shaft 13 provided with the usual sheet grippers 14. In the form of the invention selected for illustrative purposes the sheet is fed to the bottom of the sheet carrier in the manner shown 50 more fully in said prior patent, the sheet being supported on the series of sheet supports 15 carried by the rod 16, the sheet P being moved forward until its front edge

abuts against one or more of the gages 17. In the form illustrated, this gage is pivoted 55 at 18 on a longitudinally slideable member 19 provided with a projection 20 against which abuts a spring 21 between the projection 20 and a hub of a bracket 22 carried by the rod 16. A shaft 23 provided with an eccentric 24 contacts with the opposite side 60 of the projection 20. The member 19 is slidingly mounted in the bracket 22 and it is obvious that as the eccentric 24 is rotated by the turning of the shaft 23 the projection 65 20, and therefore the member 19, will be moved back and forth by the action of this eccentric 24 and the spring 21. This motion moves the gage 17 longitudinally to change its gaging position. Pivoted at 25 on the 70 bracket 22 is a member 26 having a roller 27 and a projection 28 beneath and in contact with the gage 17. A bracket 29 connected to the bracket 22 serves as the abutment for a spring 30 surrounding a rod 31 connected 75 to the member 26, the pressure of the spring 30 being transmitted through a pin 32 passing through the rod 31. The lower end of the rod 31 is screw threaded and provided with an adjusting nut 33 which, by contact 80 with the lower side of the bracket 29, limits the upward motion of the member 26.

In order to provide a sheet path in which the sheet will be guided both above and below up to the gage, we prefer to provide 85 an over-guide 40 of the type illustrated in said prior Patent No. 1,178,563, which will contact with the top of the gage 17 when the latter is in gaging position, so that the sheet passing to said gage will be held down 90 in a definite path. The height of this path is preferably changed in accordance with the thickness of the paper being fed, and to this end it is desirable to arrange the gage 17 so that the distance which it projects 95 above the upper surface of the support 15 may be varied, and the adjustment of the nut 33 provides a ready means to this end. The gage 17 rests by gravity on the projection 28 of the member 26, but if desired a 100 spring, such as a coil spring around the pivot 18, may be provided to assist the pull of gravity to keep the gage 17 always in contact with the member 26. As described in, said prior patent, the over-guide 40 is 105 lifted when the sheet is being taken by the

grippers 14, but since this entire construction as well as the wipers by which the front of the sheet is surely positioned against the gage 17, are fully described in said prior 5 patent, it will be unnecessary to repeat such description here.

In order to remove the gage 17 from the path of the sheet as the latter is taken by the grippers 14, we prefer to move the gage 10 by the direct action of the closing of the grippers and preferably by means of a cam 45 attached to the gripper shaft 13 and arranged to contact with the roller 27 on the member 26 just at the instant that the 15 grippers close on the sheet against the abutments 12. It will be understood that the cylinder 10 in the form illustrated, is moving continuously so that the motion given to the roller 27 results from the composite 20 movement due to the turning of the gripper shaft 13 and also to rotation of the cylinder. Nevertheless, the action of lifting the gage can be made very rapid with the arrangement described, and consequently such gage 25 can be allowed to remain in front of the sheet until substantially the instant that the sheet starts forward, by reason of its being gripped by the grippers 14.

We claim:

80 1. A continuously moving sheet carrier having sheet grippers thereon, a sheet gage to position a sheet in position to be taken by said grippers and means, operated by the closing of said grippers, to move said gage 85 out of the path of the sheet.

2. A sheet carrier having a gripper shaft with sheet grippers thereon, a sheet gage to position a sheet in position to be taken by said grippers, and a cam on said shaft, 40 adapted to move said gage out of the path of the sheet as the grippers close on the sheet.

3. A sheet carrier having a gripper shaft with sheet grippers thereon, a sheet gage to position a sheet in position to be taken by 45 said grippers, a yieldingly mounted member adapted to hold said gage in its gaging position, and a cam on said shaft adapted to contact with said yieldingly mounted member to move said gage out of the path of the sheet as the grippers close on the sheet.

50 4. A sheet carrier having a gripper shaft with sheet grippers thereon, a sheet gage to position a sheet in position to be taken by said grippers, means to shift said gage to 55 change its gaging position, a yieldingly mounted member adapted to hold said gage in its gaging position, and a cam on said shaft adapted to contact with said yieldingly mounted member to move said gage 60 out of the path of the sheet as the grippers close on the sheet.

5. A sheet carrier having a gripper shaft with sheet grippers thereon, a sheet gage support, a sheet gage pivotally mounted

thereon, said support being movable in the 65 direction of the travel of the sheet to change the gaging position of said gage, a yieldingly mounted pivoted member adapted to hold said gage in gaging position and to permit its gaging position to be changed, 70 and a cam on said shaft adapted to contact with said yieldingly mounted member to move said gage out of the path of the sheet as the grippers close on the sheet.

6. A sheet carrier having a gripper shaft 75 with sheet grippers thereon, a sheet gage to position a sheet in position to be taken by said grippers, a yieldingly mounted member adapted to hold said gage in its gaging position, a cam on said shaft adapted to contact with said yieldingly mounted member to move said gage out of the path of the sheet as the grippers close on the sheet, and means to adjust the normal position of said 80 yieldingly mounted member to limit the 85 distance which said gage shall extend across the path of the sheet when in gaging position.

7. A sheet carrier having a gripper shaft with sheet grippers thereon, a sheet gage 90 support, a sheet gage pivotally mounted thereon, said support being movable in the direction of the travel of the sheet to change the gaging position of said gage, a yieldingly mounted pivoted member adapted to hold said gage in gaging position and to permit its gaging position to be changed, 95 a cam on said shaft adapted to contact with said yieldingly mounted member to move said gage out of the path of the sheet as the grippers close on the sheet, and means to adjust the normal position of said yieldingly mounted member to limit the distance which said gage shall extend across the path 100 of the sheet when in gaging position. 105

8. A sheet gage support, a sheet gage pivotally mounted thereon, a yieldingly mounted member adapted to hold said gage in gaging position and means to move said 110 yieldingly mounted member to permit said gage to move out of the path of the sheet.

9. A sheet gage support, a sheet gage pivotally mounted thereon, a yieldingly mounted member adapted to hold said gage in gaging position, means to move said 115 yieldingly mounted member to permit said gage to move out of the path of the sheet, and means to adjust the normal position of said yieldingly mounted member to limit the distance which said gage shall extend across the path of the sheet when in gaging position.

10. A sheet gage support, a sheet gage pivotally mounted thereon, said support being movable to change the gaging position of said gage, a yieldingly mounted member adapted to hold said gage in gaging position and to permit its gaging position to be 125

changed, and means to move said yieldingly mounted member to permit said gage to move out of the path of the sheet.

11. A continuously moving sheet carrier having sheet grippers thereon, a gage to position a sheet in position to be taken by said grippers, a yieldingly mounted member adapted to hold said gage in gaging position, and means operated by the closing of said grippers on a sheet to move said yieldingly mounted member to permit said gage to move out of the path of the sheet.

JOSEPH WHITE.

WILLIAM ECKHARD.
